CLAIM

The ornamental design for a lab coat, as shown and described.

DESCRIPTION

FIG. 1 is a front view of a lab coat showing the claimed design;

FIG. 2 is a rear view thereof;

FIG. 3 is a left side view thereof;

FIG. 4 is a right side view thereof;

FIG. 5 is a front view of another lab coat showing the claimed design;

FIG. 6 is a rear view thereof;

FIG. 7 is a left side view thereof;

FIG. 8 is a right side view thereof;

FIG. 9 is a front view of another lab coat showing the claimed design;

FIG. 10 is a rear view thereof;

FIG. 11 is a left side view thereof;

FIG. 12 is a right side view thereof;

FIG. 13 is a front view of another lab coat showing the claimed design;

FIG. 14 is a rear view thereof;

FIG. 15 is a left side view thereof; and,

FIG. 16 is a right side view thereof.

The dashed broken lines in the figures show stitching that form part of the claimed design.

Portions of the lab coat that are not shown form no part of the claimed design.

1 Claim, 16 Drawing Sheets
